(57) **CLAIM**

The ornamental design for a smart card with a chip and a fingerprint sensor, as shown and described.

DESCRIPTION

FIG. 1 is a front perspective view of a smart card with a chip and a fingerprint sensor, showing a first embodiment of my new design;

FIG. 2 is a front elevational view of FIG. 1;
FIG. 3 is a left-side elevational view of FIG. 1, the right-side elevational view being a mirror image thereof;
FIG. 4 is a top plan view of FIG. 1, the bottom plan view being a mirror image thereof;
FIG. 5 is a front perspective view of a second embodiment thereof;
FIG. 6 is a front elevational view of FIG. 5;
FIG. 7 is a left-side elevational view of FIG. 5, the right-side elevational view being a mirror image thereof;
FIG. 8 is a top plan view of FIG. 5, the bottom plan view being a mirror image thereof;
FIG. 9 is a front perspective view of a third embodiment thereof;
FIG. 10 is a front elevational view of FIG. 9;
FIG. 11 is a left-side elevational view of FIG. 9, the right-side elevational view being a mirror image thereof;
FIG. 12 is a top plan view of FIG. 9, the bottom plan view being a mirror image thereof;
FIG. 13 is a front perspective view of a fourth embodiment thereof;
FIG. 14 is a front elevational view of FIG. 13;
FIG. 15 is a left-side elevational view of FIG. 13, the right-side elevational view being a mirror image thereof;
FIG. 16 is a top plan view of FIG. 13, the bottom plan view being a mirror image thereof;
FIG. 17 is a front perspective view of a fifth embodiment thereof;
FIG. 18 is a front elevational view of FIG. 17;
FIG. 19 is a left-side elevational view of FIG. 17, the right-side elevational view being a mirror image thereof;
FIG. 20 is a top plan view of FIG. 17, the bottom plan view being a mirror image thereof;
FIG. 21 is a front perspective view of a sixth embodiment thereof;
FIG. 22 is a front elevational view of FIG. 21;
FIG. 23 is a left-side elevational view of FIG. 21, the right-side elevational view being a mirror image thereof;
FIG. 24 is a top plan view of FIG. 21, the bottom plan view being a mirror image thereof;
FIG. 25 is a front perspective view of a seventh embodiment thereof;
FIG. 26 is a front elevational view of FIG. 25;
FIG. 27 is a left-side elevational view of FIG. 25, the right-side elevational view being a mirror image thereof;
(Continued)

FIG. 28 is a top plan view of FIG. 25, the bottom plan view being a mirror image thereof;
FIG. 29 is a front perspective view of an eighth embodiment thereof;
FIG. 30 is a front elevational view of FIG. 29;
FIG. 31 is a left-side elevational view of FIG. 29, the right-side elevational view being a mirror image thereof;
FIG. 32 is a top plan view of FIG. 29, the bottom plan view being a mirror image thereof;
FIG. 33 is a front perspective view of a ninth embodiment thereof;
FIG. 34 is a front elevational view of FIG. 17;
FIG. 35 is a left-side elevational view of FIG. 17, the right-side elevational view being a mirror image thereof; and,
FIG. 36 is a top plan view of FIG. 17, the bottom plan view being a mirror image thereof.
The rear view forms no part of the claimed design for any of the embodiments.
